UNITED STATES PATENT OFFICE

PHILIP H. HUTCHINSON, OF MONTCLAIR, NEW JERSEY, ASSIGNOR TO GENERAL MOTORS CORPORATION, OF DETROIT, MICHIGAN, A CORPORATION OF DELAWARE

GAUGE SWITCH

Application filed May 24, 1930. Serial No. 455,294.

This invention relates to gauges and comprises all the features of novelty herein disclosed. An object of the invention is to provide an improved feeler operated gauge 5 to complete one or more electric control circuits at a predetermined size or at various predetermined sizes of a work-piece which is being machined. Another object is to provide an improved gauge structure in which 10 accuracy and reliability is obtained without resort to multiplying levers or other means for magnifying motions. Other objects are to provide improved gauge devices for operating an electric contact making member at 15 a predetermined size of a work-piece and for eliminating or decreasing the deleterious effects of vibration on gauge indications or operations.

To these ends and to improve generally and 20 in detail upon devices of this character, the invention also consists in the various matters hereinafter described and claimed. In its broader aspects, the invention is not necessarily limited to the specific construction selected for illustrative purposes in the accompanying drawings in which

Fig. 1 is a side elevation of the gauge partly broken away and in section.

Fig. 2 is a front elevation with the cover 25 plate removed and with some parts in section.

Fig. 3 is an elevation of the side opposite Fig. 1, parts of the gauge being broken away and in section.

Fig. 4 is a horizontal cross section of the 30 upper portion of the gauge housing.

Fig. 5 is a front view of one of the contact carrying arms.

Fig. 6 is a side view of a slide bar.

Fig. 7 is a plan view and Fig. 8 is a front 35 view of a block and associated parts of slightly modified construction.

Fig. 9 is a plan view of the cam of Fig. 8.

The numeral 4 indicates a piece of work to 40 be ground to a predetermined size. In the present instance, the work is a hollow sleeve rotatably supported in any suitable way, preferably by rotating rollers indicated at 6, 8 and 10, while a grinding wheel 12 is re- 45 ciprocated in the bore and fed intermittent-

ly against the bore wall. A lower diamond 14, on a bent arm 16, rides on the work and supports the weight of the gauging devices therefrom. The arm 16 is fastened by screws in a slot of a vertical bracket 18. The bracket 55 has a cross groove or slot 20, dowel holes 22 and tapped holes 24 for fastening it to a pivoted supporting arm (not shown) which acts as a guide for up and down movement of the gauge. The bracket 18 is longitudinally 60 slotted as at 26 and is adjustably clamped to a gauge housing 28 by a bolt 30. The bolt has a head 32, a squared portion 33 in the slot, a round portion in the body of the housing, and a clamping nut 34. The housing is closed 65 by a removable front cover plate 36. The housing has rearwardly extending vertical ribs or guides 38 which slidably embrace the bracket 18, the ribs having projections 40 which are connected by a strap 42 extending 70 across the back of the bracket. To adjust the housing longitudinally on the bracket 18, when the clamping nut 34 is loosened, a screw 44, having an operating crank 46 is threaded in the upper end of the bracket. The screw 75 traverses the slot 26 and is journaled by a smooth shouldered extension 48 which rotates in a smooth hole in the bolt 30 and receives a retaining collar 50 at the lower end.

A bar 52 slides in the housing and its lower 80 projecting end is split as at 54 and provided with mating recesses to grip the cylindrical shank 56 of an arm 58 carrying an upper diamond 60. A clamping screw 62 passes through the split end of the bar and through 85 a groove in the shank to secure the shank firmly. The diamond 60 rides on the inner wall of the work and is held up against it by spring pressure, the upper diamond 60 and the lower diamond 14 preferably engaging 90 opposite points in the diameter of the work to measure diameter directly. The bar 52 is guided by walls 64 and 66 of the housing and is pulled upwardly by a coil spring 68 fastened at one end to a pin 70 in a recess 72 of 95 the bar, and fastened at the other end to a stud 74 in the housing. The stud 74 and the spring are contained in a recess 76 at the front of the bar. Another recess 78 is formed in the front of the bar above a lug 80 and re- 100

ceives the halved end of a block 82 which is fastened by a pair of horizontal screws 84 countersunk in the block and by a vertical screw 86 which is countersunk in a hole 88 of the bar 52. A shoulder 90 of the block fits against the side of the bar. The projecting end of the block engages the stem 92 of an indicator having a dial 94 with a pointer. The indicator will continuously show the distance 10 between the diamond points as the work is ground away. The initial reading can be changed by nuts 96 as usual to adapt the indicator for different ranges of work, the initial spacing of the diamond points for the different diameters being determined by the adjustment of the gauge housing on the bracket by the screw 44.

An important part of the invention resides in the release of electric contact making members at predetermined sizes. These contact making members may complete electric circuits of any desired character but a frequent use is to energize solenoids such as those which control reciprocation and dressing of 25 the grinding wheel. For instance, it is one practice, in internal grinding, to complete an electric circuit, when a rough grinding operation is completed, for the reduction of feed for finish grinding or the withdrawal of the 30 grinding wheel for dressing, or both. Sometimes another circuit is completed to control an additional dressing operation just before grinding is completed and usually a circuit is completed at the conclusion of grinding to 35 withdraw the grinding wheel at the exact size. In the present instance, there are three contact making members which can be reliably actuated at any selected sizes with the interval between them accurately and easily 40 determinable. Accuracy is obtained by improved mechanism which obviates the necessity for a plurality of motion multiplying levers and avoids the detrimental effects of vibration.

45 The block 82 is cut out as indicated at 98 to receive a gauge roller or hardened cylindrical plate 100 having holes 102 to receive fastening screws 104 entering the block. The plate projects below the block and engages a plurality of diamonds 106, each carried by a stud 108 in the upper end of a lever 110 pivoted on a pivot pin 112 supported by the housing. Each lever has a lateral lug or arm 114 carrying a pin 116 encircled by a coil spring 118 which exerts pressure tending to swing its lever to a released position. Each lever is split horizontally as indicated at 120, thereby making the lever springy as well as extensible and contractible within the small range desired. A screw stud 122 is threaded in each lever and has a conical portion 124 which will act as an expander as the screw is sent home or will allow contraction of the lever as the screw is turned back. Each screw is readily accessible

through an opening in the housing by swinging back a pivoted cover piece 125. The levers and their diamond points can be set initially by the aid of masters so that when the same sizes are reproduced in a product 70 piece, each diamond will reach the neutral or releasing position which lies in a vertical radius of the cylindrical plate 100. This point will be very accurately determinative due to the arc approaching more and more 75 slowly to the horizontal. The obstruction to release of the lever gradually fades to nothing and wear is distributed. Also, when the diamond lies under the plate 100, it has a locking effect on the plate and sliding parts 80 and prevents them from vibrating, by taking up the motion as fast as the work is ground. The cylindrical plate can be clamped in a reversed position by the screws 104 to distribute wear but, under some conditions, the 85 clamping screws may be omitted, as indicated in Figs. 7 and 8, to make the plate revoluble and thus provide a rolling slip release of the diamonds. Each lever carries a contact button 126 to engage a contact button 128 carried by a block of insulating material 130 fastened to the housing. When a lever is released, it goes the whole distance immediately and so makes a good and reliable contact without sparking or pitting of contact points. Each contact button 126 may be grounded through the frame of the machine, the other contact 128 being connected to a suitable insulated wire leading out to the cord connector 132.

100 The other devices in the housing have to do with the resetting of the levers and are mounted so as not to interfere with the free movement of the sliding parts. An eccentric cam 140 is mounted to turn with a shaft 142 having an operating handle 144 provided with a spring-pressed ball-detent 146. The cam engages a pin 148 which is freely slideable in an opening in the block 82. The opening also slidably receives the upper end 110 of a resetting rod 152 and a coil spring 150. A collar 154 is clamped on the rod and a light coil spring 156 is interposed between the collar and a stop block 158 which is fastened to the housing. The rod has a head or bar 160 which is held up against the stop block by the coil spring 156. The head or bar 160 overlies a portion of the lugs 114 of all three levers and is held from turning by a stop plate 162 fastened to the stop block. 115 When not in its active position, the head or bar clears the lugs so that the levers are free to move to contact completing position. The spring 156 is a weak spring just sufficient to hold the bar 160 elevated when the cam is in its inoperative position. The other spring 150 is then under little or no tension but, upon the depression of the pin 148 by the cam, the spring 150 will overcome the tension of the weak spring 156 and so cause the bar 160 to 120 125 130

swing all of the levers to initial position. The spring 150 is intended to provide for a yielding or lost-motion resetting of the levers to avoid pressing the levers forcibly against the rod 152 or its collar 154. After the cam depresses the pin 148, it engages the bar 82 and so depresses the upper diamond 60 to allow removal of the work-piece and insertion of a new piece. When restored to their inactive positions, the resetting devices do not interfere with the sliding parts of the gauge. The spring 68 exerts its pressure directly in the line of sliding and need only be strong enough to lift the sliding parts and apply an additional light pressure of the upper diamond against the work. This spring has no additional burden of releasing the contact making levers 110; the tension of the coil springs 118 tends to release the levers as the diamonds ride along the smooth and unobstructed cylindrical surface of the plate 100 but these springs cannot of themselves lift the sliding parts and cause a premature release of the levers.

The housing 28 acts as a gauge carrier and the upper arm 58 and its diamond 60 act as a movable feeler controlling movement of the plate or cylinder 100 in accordance with the changing size of the work-piece. The cylinder 100 is arranged beyond the diamond tipped ends of the levers 110 and moves bodily directly away from the levers and their pivot pin 112. The cylinder provides a curved surface which tapers or fades away transversely of its direction of movement at a point in the line connecting the pivot pin 112 to the center of curvature. The fade-out surface acts to arrest each spring-pressed lever until the diamond tipped end reaches a release point in said line and snaps past in a direction substantially tangentially of the surface and transversely of the line of movement of the cylinder. Release of the lever is facilitated by the smooth surface and the absence of any sharp obstruction at the release point.

Figs. 7, 8 and 9 indicate a modified construction wherein the spring 150 is omitted and the resetting rod 152a is carried entirely through the block to engage the cam directly. The cam has a central rib 140a which is eccentric with respect to the shaft 142, adjacent portions 164 of the cam being concentric with the shaft for their major part but projecting to form the cam projections 166. The block is provided with a central depression 168 forming a lost-motion space for the eccentric rib 140a so that rotation of the cam shaft for 180° will first lower the resetting rod 152a independently of the block and then lower the block when the cam projections engage the top of the block at opposite sides of the depression. In this modification, the contact carrying levers 110 are provided with sockets 168 for stiff coil safety springs 170

engaging bars 172 carrying the diamond holding studs, the springs pressing the bars outwardly to a definite position determined by stop pins 174 passing through the bars and engaging the upper walls of holes or slots 176 in the levers. 70

I claim:

1. In a device of the character described, a gauge carrier, a feeler movable with respect to the carrier and engaging the work to be tested, a contact carrying member movably mounted on the gauge carrier, means for urging the member towards contact making position, a plate having a curved surface arresting the contact carrying member, and means controlled by the feeler for moving the curved surface of the plate to release the contact carrying member; substantially as described. 75

2. In a device of the character described, a gauge carrier, a feeler movable with respect to the carrier and engaging the work to be tested, a contact carrying member movably mounted on the gauge carrier, means for urging the member towards contact making position, a plate having a cylindrical surface gradually approaching the contact carrying member, and means controlled by the feeler for moving the cylindrical surface bodily along a radius thereof and directly away from the contact carrying member; substantially as described. 85 90 95

3. In a device of the character described, a gauge carrier, a feeler movable with respect to the carrier and engaging the work to be tested, a contact carrying member movably mounted on the gauge carrier, means for urging the member towards contact making position, a hardened tip on the contact carrying member, a hardened cylinder having its surface engaging the tip, and means controlled by the feeler for moving the cylinder bodily away from the tip; substantially as described. 100 105

4. In a device of the character described, a gauge carrier, a feeler movable with respect to the carrier and engaging the work to be tested, a contact carrying lever pivotally mounted on the gauge carrier, means for urging the contact carrying lever towards contact making position, a plate having an arresting surface gradually fading away transversely of the lever, and means controlled by the feeler for moving the arresting surface of the plate away from the pivotal mounting of the lever; substantially as described. 110 115 120

5. In a device of the character described, a gauge carrier, a feeler movable with respect to the carrier and engaging the work to be tested, a contact carrying lever pivotally mounted on the gauge carrier, means for urging the contact carrying lever towards contact making position, a plate having an arresting surface gradually fading away 125 130

transversely of the lever, means controlled by the feeler for moving the arresting surface of the plate in the direction of the length of the lever, and means for varying the distance between the end of the lever and its pivot; substantially as described.

6. In a device of the character described, a gauge carrier, a feeler movable with respect to the carrier and engaging the work to be tested, a contact carrying member movably mounted on the gauge carrier, means for urging the member towards contact making position, a plate having a curved surface arresting the contact carrying member, a block carrying the plate, and means for causing the block to move in unison with the feeler to release the contact carrying member from the plate; substantially as described.

7. In a device of the character described, a gauge carrier, a feeler movable with respect to the carrier and engaging the work to be tested, a contact carrying member movably mounted on the gauge carrier, means for urging the member towards contact making position, a cylinder having its surface arresting the contact carrying member, a block having a recess rotatably receiving the cylinder, and means for causing the block to move in unison with the feeler to release the contact carrying member from the cylinder; substantially as described.

8. In a device of the character described, a gauge carrier, a feeler movable with respect to the carrier and engaging the work to be tested, a contact carrying member movably mounted on the gauge carrier, means for urging the member towards contact making position, a plate having a tapering surface arresting the contact carrying member, a block carrying the plate, a bar slidable on the carrier and supporting the block, and means for attaching the feeler to the slide bar; substantially as described.

9. In a device of the character described, a gauge carrier, a feeler movable with respect to the carrier and engaging the work to be tested, a contact carrying member movably mounted on the gauge carrier, means for urging the member towards contact making position, a plate having a tapering surface arresting the contact carrying member, a block carrying the plate, a bar slidable on the carrier and supporting the block, means for attaching the feeler to the slide bar, and a spring urging the plate away from the contact carrying member and pressing the feeler against the work; substantially as described.

10. In a device of the character described, a gauge carrier, a feeler movable with respect to the carrier and engaging the work to be tested, a plurality of contact carrying members movably mounted on the gauge carrier, means for individually urging the contact carrying members towards contact making

position, a plate having a tapering surface arresting the contact carrying members, means for individually setting the contact carrying members with respect to the plate, and means for causing the plate to move in unison with the feeler to release the contact carrying members successively from the plate; substantially as described.

11. In a device of the character described, a gauge carrier, a feeler movable with respect to the carrier and engaging the work to be tested, a contact carrying member movably mounted on the gauge carrier, means for urging the member towards contact making position, a plate having a curved surface for arresting the contact carrying member, means for moving the plate in unison with the feeler to release the contact carrying member, and a cam for first returning the contact carrying member, and for thereafter returning the plate to arresting position; substantially as described.

12. In a device of the character described, a gauge carrier, a feeler movable with respect to the carrier and engaging the work to be tested, a contact carrying member movably mounted on the gauge carrier, means for urging the member towards contact making position, a plate for arresting the contact carrying member, means for moving the plate in unison with the feeler to release the contact carrying member, a cam, a spring-pressed rod actuated by the cam to return the contact carrying member, and means subsequently actuated by the cam for returning the plate to arresting position; substantially as described.

13. In a device of the character described, a gauge carrier, a feeler movable with respect to the carrier and engaging the work to be tested, a contact carrying member movably mounted on the gauge carrier, means for urging the member towards contact making position, a block having means for arresting the contact carrying member, and controlled by the feeler to release the contact carrying member, a rod slidable in the block to return the contact carrying member, and means to successively actuate the rod and the block; substantially as described.

14. In a device of the character described, a gauge carrier, a feeler movable with respect to the carrier and engaging the work to be tested, a plurality of contact carrying members movably mounted on the gauge carrier, means for urging the members towards contact making position, a block having means for arresting the contact carrying members and controlled by the feeler to release the contact carrying members, a rod slidable in the block and having a head to return the contact carrying members to arrested position, and means to successively actuate the rod and the block; substantially as described.

15. In a device of the character described, a gauge carrier, a plate movable with respect to the carrier to a position determined by a dimension of the work to be tested, a contact carrying member supported by the carrier and movable transversely to the direction of movement of the plate, the plate having an arresting surface gradually fading out in said transverse direction and engaging said contact carrying member, and means for urging said member past said fade-out point when the plate reaches said position determined by the dimension of the work; substantially as described.
16. In a device of the character described, a gauge carrier, a plate supported by the carrier and movable thereon to a position determined by a dimension of the work, a contact carrying lever pivoted at one of its ends to the carrier and having its other end in engagement with the plate, the plate having a curved surface whose center of curvature is beyond the end of the lever, and a spring urging the lever in a direction to carry its plate-engaging end towards a radius of the curved surface; substantially as described.
17. In a device of the character described, a gauge carrier, a contact carrying lever pivoted at one of its ends to the carrier, a plate supported by the carrier and movable thereon in a direction directly away from the pivot of the lever to a position determined by a dimension of the work to be tested, the plate having a curved surface engaging the free end of the lever and approaching more and more slowly to a release point in the line connecting the pivot of the lever to the center of curvature of said surface, and a spring urging the free end of the lever along said surface towards said point of release as the plate recedes from said pivot; substantially as described.

In testimony whereof I hereunto affix my
signature.

43 PHILIP H. HUTCHINSON.
